UNITED STATES PATENT OFFICE.

GEORGE C. FRISBIE, OF CEASE'S MILLS, PENNSYLVANIA.

THILL-COUPING.

SPECIFICATION forming part of Letters Patent No. 391,701, dated October 23, 1888.

Application filed July 31, 1888. Serial No. 281,487. (No model.)

To all whom it may concern:

Be it known that I, GEORGE C. FRISBIE, a citizen of the United States of America, residing at Cease's Mills, in the county of Luzerne 5 and State of Pennsylvania, have invented certain new and useful Improvements in Thill-Couplings, of which the following is a specification, reference being had therein to the accompanying drawings.

10 This invention pertains to certain new and useful improvements in combined thill-couplings and devices for detaching horses from vehicles; and it comprises the detail, construction, combination, and arrangement of parts 15 substantially as hereinafter fully set forth, and particularly pointed out in the claims.

In the accompanying drawings, Figure 1 is a front elevation of my invention. Fig. 2 is a cross-sectional view on the line $x-x$, Fig. 1; 20 and Fig. 3 is a detail perspective view.

Referring to the drawings, A designates the front axle of a vehicle, and $a-a$ the ordinary clips, from each of which project two apertured ears, $a'-a'$.

25 B B are two clips secured to axle A at points adjacent the clips a , and the lower threaded ends of these clips B are extended through apertures of yokes C C and are fitted with nuts, which secure said yokes in place. The outer 30 ends of these yokes C are bent upwardly, and their extreme ends are rounded, as shown, forming eyes or loops $b-b'$, as shown.

A third yoke plate or arm, D, is attached to axle A, near the center thereof, and is provided 35 with an upwardly-projecting hooked or bent end, d .

E E are two sliding rods or arms, which are projected through and guided by the eyes or loops b of yokes C, and the ends of said rods 40 or arms are designed to work in the apertured ears a' of end clips, a . One of these rods or arms is provided with a ring or collar, a^2 , to limit the movement thereof. The inner ends of these rods or arms E are pivotally connected 45 to a lever, e , fulcrumed on a stud, e' , of a plate, e^2 , attached to axle A, said rods or arms being

secured at equal distances from the fulcrum of said lever. When in an approximately horizontal position, this lever E is held by the hooked end of yoke or arm D, and when thus 50 held the ends of rods or arms E are held extended through the ears of the end clips, thereby effecting the coupling of the thill-irons to said clips.

To uncouple or detach the thills, the lever e 55 is withdrawn and lowered into a vertical position.

I am aware that it is not new to employ a centrally-pivoted disk having a lever and outwardly-projecting arms, the ends of which secure the thills; and hence I do not lay claim to such construction, my invention being designed as an improvement thereon, embodying as it does advantages in point of simplicity, durability, and general efficiency. 65

I claim as my invention—

1. As an improvement in combined thill-couplings and devices for detaching horses, the two sliding rods or arms, the lever fulcrumed upon a centrally-disposed plate, and the yoke 70 plate or arm D, having a bent or hooked end by which the end of said lever is held, substantially as shown and described, said rods or arms being secured to said lever, as stated.

2. The combination, with the axle and the 75 clips having apertured ears, of the horizontally-disposed rods or arms, the central lever to which said rods or arms are secured, the fulcrum stud or pin, together with its plate, secured to said axle, the yoke plate or arm D, having a bent or hooked end by which lever is held in a horizontal position, the clips B, and the yoke-plates C C, having eyes or loops for guiding said rods or arms, substantially as described. 85

In testimony whereof I affix my signature in presence of two witnesses.

GEORGE C. FRISBIE.

Witnesses:

JAMES ELEY,
H. B. VAN HORN.
